ATTORNEY.

UNITED STATES PATENT OFFICE.

ELMER E. GRAFFTEY, OF KANSAS CITY, MISSOURI.

CLEANSER.

1,214,025.

Specification of Letters Patent. Patented Jan. 30, 1917.

Application filed March 10, 1916. Serial No. 83,419.

To all whom it may concern:

Be it known that I, ELMER E. GRAFFTEY, a citizen of the United States, residing at Kansas City, in the county of Jackson and State of Missouri, have invented certain new and useful Improvements in Cleansers, of which the following is a specification.

My invention relates to brushes of that type in which the bristles or fibers are removably held in a hollow brush head, so that when worn out they can be readily replaced with others.

An important feature of the present invention resides in a tubular tuft holder having ports communicating with the interior of the hollow brush head, so that a cleansing fluid therein may flow out through the ports and thus keep the bristles or fibers constituting the tufts clean and in a sanitary condition.

While adaptable to a large variety of uses, my brush is particularly adapted for use in packing houses for cleansing carcasses, and the interior of cans before the same are filled with food products, and since the brush is self-cleansing the tufts need not be discarded on sanitary grounds until worn out.

Other features of the invention will hereinafter appear, and in order that said invention may be fully understood, reference will now be made to the accompanying drawing, in which:

Figure 1 is a longitudinal section of a brush made in accordance with my invention. Fig. 2 is a cross section on line II—II of Fig. 1. Fig. 3 is a detail perspective view, enlarged, of a tubular member forming an important feature of the invention. Fig. 4 is a vertical section of the tubular member. Fig. 5 is a section of a modified form of brush with the tubular members formed integral with the brush head.

Referring now to the drawing, in which similar reference numerals correspond with similar parts throughout the several views: 1 designates the brush head which may be of either wood, metal, or other suitable material, and is, preferably, of hollow construction to provide a chamber for holding steam, or other cleansing agents, such, for instance, as water, liquid soap, etc.

The steam or liquid is supplied to the hollow head 1 through a coupling 2, to which a hose (not shown) may be attached. When only a small quantity of liquid is to be used,

the hollow head is filled therewith and the coupling 2 is then closed with a cap 3.

4 designates a socket fixed to the top of the head 1 and adapted to receive a handle 5, whereby the brush may be conveniently manipulated.

6 designates a plurality of tubular members in which the bristles or fibers 7 are reliably secured by wires or other suitable elements 8, so that when worn out said bristles can be readily replaced with others.

Each tubular member 6 has screw threads 9 at its lower portion adapted to be screwed into correspondingly threaded apertures in the bottom of the brush head. Peripheral shoulders 10 at the lower ends of the members 6 are provided to abut the lower surface of the bottom of the brush and thus limit the entrance of the members 6 therein. 75 The upper portion 11 of each element 6 is of truncated conical form and has two oppositely disposed openings 12 and a top opening 12^a, through which its respective wire 3 is threaded and through which steam or liquid may flow from the hollow brush head. The lower portion of each element 6, also has oppositely-disposed ports 13 through which steam or liquid in the hollow head 1 discharges and freely flows around 85 the bristles 7, keeping the same free of foreign matter and in a clean and thoroughly sanitary condition during the operation of washing any surface over which said bristles may be rubbed. The truncated upper portion 90 11 of the element 6 forms an abutment for the upper end of its respective tuft and not only relieves the retaining wire 8 of all strain, but prevents the fibers being cut on said wire as would be the case if the latter 95 had to withstand the upward pressure of said tuft while the same is being forced over a surface to be cleaned.

The tubular members 6 are made of any suitable material and any desired number 100 may be employed, and while I have shown them applied to a hollow rectangular brush head, it is to be understood that they may be connected to any desired form of head whether it be chambered or solid.

In the modified form disclosed by Fig. 5, the tubular members 6^a are formed integral with the bottom of the hollow head 1^a, which has a removable top 1^b, so that access may be had to the wires when the tufts are 110 to be secured in, or removed from said members 6^a.

2

From the foregoing description, it is apparent that I have produced a simple, inexpensive and sanitary brush embodying all of the features of advantage above-mentioned.

Having thus described my invention, what I claim and desire to secure by Letters Patent, is:

In a device of the character described, in combination, a tubular member adapted to receive a tuft of bristles or fibers and provided with a conical terminal to abut the inner end of said tuft, said tubular member

having a shoulder at its opposite end surrounded by screw threads, ports in said tubular member, means for securing the tuft in said tubular member, and a brush head into which the tubular member is adapted to be screwed.

In testimony whereof I affix my signature, 15 in the presence of two witnesses.

ELMER E. GRAFFTEY.

Witnesses:

F. G. FISCHER,
